STUBBING DEVICE

Rolland G. Williams, Branford, Conn., assignor
to Malleable Iron Fittings Company, Branford,
Conn., a corporation of Connecticut

Application June 16, 1933, Serial No. 676,083
Renewed March 27, 1935

17 Claims. (Cl. 20—99)

This invention relates to stubbing devices and more particularly to devices for securing together two adjacent poles or securing the base of one pole to a stub pole, as is sometimes necessary.

5 After the poles of telephone lines or electric light lines, or the like, have been in the ground for a period of time they are subject to decay at or below the ground line and become quite weak at this point. It is either necessary to remove 10 the pole and install a new one or in some way provide means for making the base of the pole secure. If the pole is removed and a new one installed, it means, of course, that the wires, cross arms, etc., must all be removed from the old pole 15 and placed on the new one, so that aside from the necessary new equipment, a considerable amount of labor is involved.

It has been found satisfactory in many instances to avoid replacing the pole with a new 20 one by inserting a stub pole or short pole into the ground adjacent the old one which has become decayed, leaving several feet of the stub pole projecting above the ground line. The old pole is then secured to the projecting portion of the stub 25 pole by passing straps or bands around both and securing them as tightly together as possible. It is, of course, desirable that the means for securing the poles together be so arranged that the old pole will be secured rigidly and firmly to the 30 stub, and to this end it is advantageous to provide means for drawing the straps or bands tightly about the poles after they have been mounted thereon.

It is also desirable to connect the parts of the 35 securing means so that there will be no relative slippage or movement between such parts and no tendency of one part to roll or slide on the other.

One object of my invention is the provision of 40 a new and improved stubbing device or means for securing adjacent poles together, such that the device may be readily and easily secured in place and serve to bind the two poles rigidly and securely together.

Another object of the invention is the provision 45 of a stubbing or pole-securing device having provision whereby the straps or bands which embrace the pole may be tightened or drawn together by bolts passing between the poles, the bolt-securing devices being so arranged that there 50 will be no possibility of movement between them and the pole-embracing straps.

A still further object of the invention is the provision of a pole-securing or stubbing device 55 which will be positive and efficient in operation

and at the same time may be economically manufactured and readily installed in place.

To these and other ends, the invention consists in the novel features and combinations of parts to be hereinafter described and claimed. 5

In the accompanying drawings:

Fig. 1 is a side elevational view of a pole and stub pole upon which my improved device is mounted;

Fig. 2 is a sectional view on line 2—2 of Fig. 1; 10

Fig. 3 is an enlarged sectional view on line 3—3 of Fig. 1;

Fig. 4 is a sectional view of the bracket substantially on line 4—4 of Fig. 3;

Fig. 5 is a front elevational view of a modified 15 form of stubbing device applied to a pair of poles;

Fig. 6 is an enlarged sectional view on line 6—6 of Fig. 5;

Fig. 7 is a view similar to Fig. 5 showing a further modified form of stubbing device; 20

Fig. 8 is a sectional view on line 8—8 of Fig. 7;

Fig. 9 is an end elevational view of the bracket shown in Figs. 7 and 8;

Fig. 10 is a rear elevational view of the bracket shown in Figs. 7, 8 and 9. 25

To illustrate one preferred embodiment of my invention, I have shown a pole 10 which has been cut off as at 11 adjacent the ground line 12 and secured by my improved securing devices to a stub pole 14 set into the ground adjacent the pole 10 and permitted to project several feet above the ground line beside, and closely adjacent to, the pole 10. 30

As illustrated, a U-shaped rod or bolt 15 is employed to embrace the outer side of each of the 35 poles 10 and 14. These members 15 may be of any desired shape, either flat or round in cross section, so far as concerns the main portions of their lengths. The ends of these members, however, are preferably round so as to be threaded, as at 16, 40 to receive the nuts 17.

The adjacent ends of the members 15 are connected together, as shown in Figs. 1 to 3, by means of bracket members designated generally by the 45 numeral 18. These brackets consist of end portions 19 which may be suitably curved to present a surface of substantially arcuate shape to lie closely adjacent the poles, and intermediate or web portions 20 connecting the curved ends and lying adjacent the space between the poles. 50

The web portions 20 are provided with openings 21 to receive a bolt 22 which upon one end will preferably be provided with threads to receive the nut 23 so that the nut may be taken up upon the bolt and tend to draw the bracket members to- 55

ward the poles. It will be understood that the bolt 22 passes between the adjacent poles.

The end members 19 of the brackets may be bifurcated as shown at 24 and provided with up-

5 standing lugs 25 having slots 26 provided therein to receive the ends of the U-shaped members or bolts 15. Flanges 27 may be provided upon the lugs 25 adjacent the slot 26, against which flanges the nut 17 may bear so that when the nuts are 10 taken up upon the bolts 15 the latter will be drawn tightly against the outer surfaces of the poles.

The web portion 28 of the bracket may be provided with a boss 29 about the opening 21 and also be provided with upper and lower flanges 28 to 15 strengthen the central portion of this part of the web and prevent it from bending too sharply when the web portions of the brackets are drawn together by the bolt 22.

In installing the device, the members 15 are 20 placed about the pole and their threaded ends inserted through the slots 26 in the lugs 25. Nuts 17 are then placed upon the threaded ends of the members 15 and taken up to draw the members 15 as closely as possible about the outer sides of the 25 poles. When this has been done the bolt 22 is passed through the openings 21 and the nut 23 taken up upon the end thereof to draw the web portions 28 of the brackets 18 inwardly toward the poles and effect a consequent additional drawing action upon the members 15 to cause these 30 members to engage the poles more tightly. The web portions 28 of the brackets will ordinarily be sufficiently resilient to permit this result to be accomplished.

35 It will be understood that due to the shape of the end portions 19, and due to the fact that the bolt 22 is secured to the bracket members by passing through openings therein, the bracket members will be held in their initial positions upon the poles and will have no tendency to travel. Moreover, by providing for taking up any slack or 40 looseness both at the ends of the bolts 15 and by means of drawing the brackets together by the bolt 21, it will be possible to secure the two poles 45 rigidly together so as to make the most rigid connection between them.

As shown in Fig. 1, two of my devices are employed in connection with the poles 10 and 14. It 50 will be understood, however, that any suitable number of these devices may be employed, depending upon the size and height of the poles.

In Figs. 5 and 6 of the drawings I have shown a stubbing device having a bracket 30 of somewhat modified form. This bracket is similar in 55 some respects to the bracket 18 shown in Figs. 1 to 4. The bracket 18, however, is intended to be somewhat resilient so that its central portion will draw in between the poles and thus cause the bolt or embracing members 15 to bind tightly 60 around the poles. The bracket 30 is designed to be of the rigid type and effects a binding action of the bolts 15 by drawing in the ends thereof from the position in which these ends stand when they are inserted through openings of the bracket. That is, in this instance, the entire 65 bracket will move inwardly toward the poles instead of the bracket itself being bent out of its original shape.

The bracket 30 has a central V-shaped web 70 portion 31 and side flanges 32 and 33, these flanges being of such a nature that they will stiffen the web portion of the bracket and prevent any appreciable bending thereof. At their ends 75 the flange portions 32 and 33 are connected by end flanges 34 and 35, provided with slotted open-

ings 36 and 37 through which the ends of the bolts 15 are designed to be inserted. Nuts 17 may then be threaded upon these bolts to take them up until they are set closely to the poles.

The central web portion 31 of the bracket 30 is 5 provided with an elongated bolt opening 38 to receive the bolt 39 passing between the poles, as has already been explained in connection with the form of my device shown in Figs. 1 to 4 of the drawings. The surface of the web 31 about the opening 38 is rounded, as shown at 40, to provide a seat or socket for a washer 41, placed upon the bolt 39. This washer has its lower surface rounded to some extent to fit against and rock over the surface 40.

10 It will be understood that in this form of my device there will be a bracket 38 upon each side of the pair of poles, or the pole and stub pole, as the case may be. After the bolts 15 have been placed in an embracing position about the poles, 20 their ends are inserted through the openings 36 and 37 and the nuts 17 tightened thereon. The bolt 39 will then be inserted through the brackets and the nut 40 taken up to draw the brackets towards the poles and thus cause the bolts 15 to 25 bind tightly about the latter. It will sometimes be found that the openings 38 do not exactly register upon opposite sides of the poles or that the bolt 39 when passed through these openings does not occupy a position coinciding with the 30 axis of the openings 38. It is for this reason that these openings are slotted or enlarged with respect to the bolt 39 in a direction longitudinally of the web 31. As the washer 41 upon the bolt 39 is provided with a rounded lower surface 35 complementary to the surface of the seat or socket 40, this washer will tend to seat itself in the proper position so as to permit the bolt 39 to lie at an angle to the axis of the opening if it naturally assumes such a position. This provides for an 40 easy insertion of the bolt 39 and also relieves strain upon the parts while in use.

In Figs. 7 to 10 of the drawings I have shown a further modified form of my invention wherein bolts or embracing members 15 are placed about 45 the poles and have their ends received and held in brackets 45. Each of the bracket members 45 consists of a front plate member 46, provided with a central opening 47 and having upper and lower flanges 48 and 49 projecting rearwardly from the 50 front face so as to project toward the poles when the bracket is in place. Strengthening web members 50 and 51 may be provided at the central portion of the bracket adjacent the opening 47, these web members forming in conjunction with the flanges 48 and 49, channels or sockets 52 and 53 upon the rear side of the plate 46 to receive the ends of the bolts 15. At the ends of these channels are provided web members or lugs 54 and 55 having openings 56 and 57 through which 60 the ends of the bolts may pass for the reception of the nuts 17.

65 It will be apparent that in the use of this form of device the ends of the bolts overlap as each enters one side of the bracket, and passes through the same to have its threaded end project from the opposite side. In the form shown, the brackets used upon opposite sides of the bolt are duplicates and for this reason the bolt 15, which enters the upper channel 52 upon one side of the 70 pole, will enter the lower channel 53 of the bracket upon the other side of the pole.

75 For this reason the bolts 15 are not in a true horizontal position and it will be seen that the channels 52 and 53 are slightly inclined to allow 75

for this departure from the horizontal, that is, the openings or notches 58 and 59 between the webs 54 and 55 and the flanges 49 and 48, will not be in true horizontal alignment with the 5 openings 56 and 57, and the side edges of the bracket, as shown in Fig. 7, are not precisely at right angles to the upper and lower edges. When the fitting has been installed, however, and tension applied to the bolts, the side edges of the 10 brackets will be drawn substantially to a vertical position. If desired, the brackets might, of course, be made right and left-hand so that both ends of one of the bolts would enter the upper channels or the lower channels, as the case may 15 be.

It will also be apparent that as the ends of the bolts are at different levels in the brackets, the tension thereon will exert a force which will act as a couple, tending to turn or cant the bracket 20 from the position in which it is first installed. This will, of course, be resisted by contact of the bolts against the surrounding material of the bracket, as any great amount of canting of the bracket would serve to bend the ends of the bolts.

When the fitting shown in Figs. 7 to 10 is installed, the bolts 15 are placed about the poles and their ends inserted through the channels 52 and 53 and the nuts 17 drawn up upon the bolts. The bolt 60 is then inserted through the openings 57 and the nut 61 drawn up to urge the brackets toward the poles and thus cause the bolts to bind tightly about the poles.

By inspection of Fig. 8 it will be seen that when the bracket 45 is drawn inwardly the bolts 15 will assume a position against the front plate 46. If a continued inward movement of the bracket is effected this will cause a reverse bending of the end of the bolt adjacent the edge of the bracket, which will, of course, be resisted by considerable 40 force. Prior to this time, however, the ends of the bolts will be drawn inwardly from the positions in which they stood when they were inserted into the brackets, and the bolts will in all probability be tightly bound to the poles when the fitting reaches the position shown in this figure of the drawings.

While I have shown and described some preferred embodiments of my invention, it will be understood that it is not to be limited to the details shown but is capable of modification and variation within the spirit of the invention and the scope of the appended claims.

What I claim is:

1. In a device for securing together a pair of adjacent poles, a U-shaped member embracing the outer side of each of the poles, brackets on opposite sides of the poles, the adjacent ends of said members being secured to the brackets in spaced relation, and a bolt passing through openings in said brackets between the ends of said members and between said poles to draw said brackets toward each other and tighten said U-shaped members about the poles.

2. In a device for securing together a pair of adjacent poles, a U-shaped member embracing the outer side of each of the poles, brackets connecting the adjacent ends of said members together, a bolt passing through openings in said brackets and between said poles to draw said brackets toward each other and tighten said U-shaped members about the poles, the adjacent ends of said U-shaped members being adjustably secured to said brackets in spaced relation and said openings lying between said ends of the U-shaped members.

3. In a device for securing together a pair of adjacent poles, a U-shaped member embracing the outer side of each of the poles, brackets connecting the adjacent ends of said members together, a bolt passing through openings in said brackets and between said poles to draw said brackets toward each other and tighten said U-shaped members about the poles, and said brackets being provided with perforated lugs to receive the ends of said U-shaped members and adjusting nuts on the ends of said members whereby they may be adjusted to the poles. 5

4. In a device for securing together a pair of adjacent poles, a U-shaped member embracing the outer side of each of the poles, brackets extending between the ends of said U-shaped members to connect them together, each of said brackets having an intermediate web portion provided with an opening, and end portions having outwardly projecting slotted lugs thereon, the 20 ends of said U-shaped members being adjustably secured in the slots of said lugs, and means passing through the openings in the web portion of said brackets and passing between the poles to draw the brackets together. 25

5. In a device for securing together a pair of adjacent poles, a U-shaped member embracing the outer side of each of the poles, brackets extending between the ends of said U-shaped members to connect them together, each of said 30 brackets having an intermediate web portion provided with an opening, and end portions having outwardly projecting slotted lugs thereon, the ends of said U-shaped members being adjustably secured in the slots of said lugs, means passing 35 through the openings in the web portion of said brackets and passing between the poles to draw the brackets together, and means formed on the web portions of said brackets adjacent the openings therein to prevent excessive bending of the 40 bracket.

6. In a device for securing together a pair of poles, U-shaped members embracing the outer side of each of the poles, the ends of one member being spaced from those of the other member, bracket members to secure the said ends together, each of said brackets comprising a web portion bridging the space between the poles and end portions lying against the poles, said web portion being provided with an opening to receive a bolt, and said end portions being formed with slots to receive the ends of said U-shaped 45 members. 50

7. In a device for securing together a pair of poles, U-shaped members embracing the outer side of each of the poles, the ends of one member being spaced from those of the other member, bracket members to secure the said ends together, each of said brackets comprising a web portion bridging the space between the poles and end 60 portions lying against the poles, said web portion being provided with an opening to receive a bolt, and said end portions being bifurcated and provided with outwardly projecting slotted lugs to receive the ends of said U-shaped members. 65

8. In a device for securing together a pair of adjacent poles, an embracing member embracing the outer side of each of the poles, brackets positioned in the spaces between the poles in opposite sides thereof and connecting the adjacent ends 70 of said members together, each of said brackets having an intermediate body portion and end members projecting from the body portion, said end members being provided with openings to receive said embracing members, and said body 75

portion being provided with an opening to receive a member connecting the brackets upon opposite sides of the poles.

9. In a device for securing together a pair of adjacent poles, embracing members embracing the outer side of each of the poles, bracket members to which the ends of said embracing members are secured, each of said bracket members comprising a body portion spanning the spaces between the poles and having a substantially centrally disposed opening, means passing through said openings to draw the members together, projecting end members adjacent the ends of the body members, said end members being provided with openings to receive the ends of the embracing members, and means adjustably mounted on said embracing members to secure them to said projecting members.

10. A bracket for use with a stubbing device or the like, said bracket comprising a substantially V-shaped body portion having an opening intermediate its ends, upstanding end members at the ends of said body portion, side flanges at the side edges of the body portion and connecting the end portions, and said end portions having openings therein.

11. A bracket member for use with a pole-stubbing device, said bracket member comprising a body portion and flanges projecting rearwardly therefrom at the upper and lower edges thereof, and web members projecting rearwardly from the side edges of the bracket and provided with bolt-receiving openings therein.

12. A bracket member for use with a pole-stubbing device, said bracket member comprising a body portion and flanges projecting rearwardly therefrom at the upper and lower edges thereof, web members projecting rearwardly from the side edges of the bracket and provided with bolt-receiving openings therein, and said bracket being provided with bolt-receiving channels at the rear side of the body portion in alignment with the openings in the web members.

13. In a pole-stubbing device, an embracing member adapted to embrace the outer side of each of two adjacent poles, brackets at opposite sides of the poles and adapted to have the ends of said embracing member secured thereto, said brackets comprising a body member having side web members projecting rearwardly therefrom, said web members being provided with openings therein, the web member upon one side of the bracket being disposed above that upon the other side of the bracket, and means passing through said brackets and between the poles to secure the brackets together.

14. In a pole-stubbing device, an embracing member adapted to embrace the outer side of each of two adjacent poles, brackets at opposite sides of the poles and adapted to have the ends of said embracing member secured thereto, said brackets comprising a body member having side web members projecting rearwardly therefrom, said web members being provided with openings therein, the web member upon one side of the bracket being disposed above that upon the other side of the bracket, and means passing through said brackets and between the poles to secure the brackets together, said brackets having upper and lower rearwardly projecting flanges, said flanges being spaced from said adjacent web members to provide an opening for the entrance of said embracing members.

15. In a pole-stubbing device, an embracing member adapted to embrace the outer side of each of two adjacent poles, brackets at opposite sides of the poles and adapted to have the ends of said embracing member secured thereto, said brackets comprising a body member having side web members projecting rearwardly therefrom, said web members being provided with openings therein, the web member upon one side of the bracket being disposed above that upon the other side of the bracket, and means passing through said brackets and between the poles to secure the brackets together, said brackets having upper and lower rearwardly projecting flanges, said flanges being spaced from said adjacent web members to provide an opening for the entrance of said embracing members, and said openings being substantially in line with the opening in the opposite web member.

16. In a device for securing together a pair of adjacent poles, means embracing said poles, members positioned on opposite sides of the poles, means for securing said members to said embracing means to prevent slippage of the latter, and means passing between the poles to draw said members toward the poles to bind the embracing means closely thereto, said last-named means passing through said members and being disposed without said embracing means.

17. In a device for securing together a pair of adjacent poles, a pair of strap-like members embracing the poles, brackets disposed in the space between the poles on opposite sides thereof, said brackets being secured to said strap-like members, and means passing between the poles without said strap-like members and secured to said brackets to draw the latter together to cause the strap-like members to tightly embrace the poles.

ROLLAND G. WILLIAMS.
